UNITED STATES PATENT OFFICE

GEORGE F. WOLFF, OF CHICAGO, ILLINOIS, ASSIGNOR TO SAGER METAL WEATHER-
STRIP CO., OF CHICAGO, ILLINOIS, A CORPORATION OF ILLINOIS

METAL WEATHER STRIP

Application filed December 26, 1925. Serial No. 77,701.

My invention relates to metal weather stripping.

One of the objects of my invention resides in providing a simple construction of weather stripping which can be cut to desired length and applied merely by tacking it in place.

Another object of my invention resides in providing a stripping which is cheap to manufacture, easy to apply, and combines rigidity and wearing qualities with maximum effectiveness in providing the necessary seal between the relatively movable parts, such as the bottom of the door and the threshold.

A further object of my invention resides in providing a novel construction of sheet metal stripping having hemmed edges and wherein the sealing portion of the stripping intermediate these edges is free from the objectionable undulated or wavy portions generally caused by the edge hemming operation.

Yet another object of my invention resides in providing a novel construction of sheet metal stripping adapted in particular for installation on the bottom of a swinging door, comprising an integral strip having an attaching flange and a deflectable sealing flange, substantially bow or rocker shaped in cross section with its outer edge freely contacting the undersurface of the door and the bowed surface of the deflectable flange contacting the surface of the threshold.

Still another object of my invention resides in providing a metal strip of the above described character with one or more longitudinal scores whereby to provide a high contacting surface extending longitudinally of the stripping so as to make firm, yet yieldable contact with the threshold when the door is closed.

A further object of my invention resides in providing a construction wherein the free edge of the strip is curved upwardly into contact with the bottom of the door whereby to clear the floor on either side of the threshold and wherein the intermediate portion of the attached strip is substantially bowed, whereby it is caused resiliently to press against the threshold when the door closes.

Numerous other objects and advantages of the invention will be apparent as it is better

understood from the following description, which, taken in connection with the accompanying drawings, discloses a preferred embodiment thereof.

Referring to the drawings,

55

Figure 1 is a view of a door partly in section with my improved weatherstrip attached,

Figure 2 is an end view of the strip itself,

Figure 3 is plan view of the strip.

While it must be evident that my improved strip is capable of installation on various moving parts to seal the space therebetween, it is particularly adaptable as a weather strip for the bottom of a swinging door and especially of the type illustrated in Figure 1 60 of the drawings which illustrates a door that swings in one direction, being limited in the opposite direction by the usual door frame.

In details of construction, my improved strip is made of suitable substantially flat resilient metal, for instance sheet-bronze, cut into relatively long strips. As shown in Figure 2, such a strip is bent approximately at the point 2 to provide a flat, straight side or flange 3 adapted for attaching the strip to the side of the bottom of the door 4, somewhat as illustrated in Figure 1. This may be done by tacking it in place. It will be noticed that the edge 5 of this strip is hemmed as at 6 to conceal raw edges and provide durability. 70

Continuing from the point of bend 2, the strip extends substantially at right angles as at 7 and thence curves gradually upwardly, somewhat in the form of a bow or rocker 8 with the free end 9 hemmed to conceal the raw edge 85 and provide durability and smoothness at the edge for a purpose hereinafter made evident. In cross section, the portions 7 and 8 of the strip are rather cradle shape in cross section. This forms a most useful function.

When the strip is tacked in position and the door 4 is open, the portions 7 and 8 of the strip which form a freely deflectable, resilient, flange assume more of the shape disclosed in Figure 2 of the drawings, the edge 95 9 of the strip lying snugly against the undersurface of the door so as not to catch or scrape along the floor or carpet.

When the door is swung to closed position, the deflectable flange portion 7 and 8 is some- 100

what compressed against the top of the threshold so that the strip takes more of the position shown in Figure 1, where it is shown tightly pressing against and sealing the joint 5 between the bottom of the door and the threshold. During the flexing of the flange 7 and 8 the hemmed, free edge 9 rides smoothly against the door bottom.

The sealing flange portion 7, 8 of the strip 10 is provided with means more securely to seal the joint by eliminating the usual crinkles, or buckles formed in the metal during the hemming of the edges, and in addition to lend 15 rigidity and strength to the strip; this latter feature is most advantageous when it is considered that the strip is made of rather resilient sheet metal and of such convenient thickness that it may easily be cut to length and also that it may possess inherent resiliency and lightness.

To accomplish these objects, the strip is provided with one or more longitudinally arranged scores, tracks or lines depressed into the metal as at 10 so as to provide on each 25 side thereof raised or high portions of the strip which form continuous sealing surfaces lengthwise of the strip. This wrinkling of the metal formed during the beading operation or formed by the bend 2 is brought about 30 due to the fact that when the bend or beads are formed the metal is stretched at the point by reason of the pressing rolls or by reason of the bending operation, and since the metal is not stretched at intermediate points the 35 wrinkles are formed. My process for eliminating these objections of wrinkles resides in suitably deforming this intermediate metal, and one of the ways of deforming it resides in forming the score lines longitudinally of the 40 metal. Obviously, any other method of deforming the metal is within the contemplation of my invention.

In addition, these scores 10 function to eliminate the waves or wrinkles which have 45 heretofore been permanently formed on the strip by the preceding hemming operation, and which are highly objectionable since they prevent a snug fit at every point on the undersurface of the strip. Furthermore, these 50 tracks 10 lend considerable rigidity to the strip and brace it lengthwise against bending. This is important because in handling, the strip is liable to bend and create weak spots and splits.

55 It must be evident that by my construction a most advantageous strip is provided; one that forms a metal cushion against which the door will close, which is easily installed, and which will not catch or scratch against the floor or carpet when the door is swung to open position.

60 It is thought that the invention and many of its attendant advantages will be understood from the foregoing description, and it 65 will be apparent that various changes may

be made in the form, construction and arrangement of the parts without departing from the spirit and scope of the invention, or sacrificing all of its material advantages, the form hereinbefore described being merely a preferred embodiment thereof.

I claim:

1. A weather stripping comprising a length of substantially flat sheet-metal bent to form a substantially bowed portion and an 75 angularly disposed integral attaching flange of substantially flat cross section, the free edges of the strip being hemmed, said strip being provided with reinforcing ribs extending longitudinally of the strip.

2. A weather stripping comprising a length of substantially flat, sheet-metal bent to form a substantially bowed portion and an angularly disposed integral attaching flange of substantially flat cross section, the 85 intermediate portions of the strip being provided with a desired number of scores to eliminate wrinkles and to strengthen the strip.

3. The combination of a door bottom and threshold therebeneath, a weather stripping 90 having a vertically extending part secured to a vertical face of the door near the bottom surface thereof, and a part extending down and curved up into engagement with the bottom face of said door and arranged with its 95 edge normally in contact therewith, said edge being freely slideable with the bottom face of the door, the weather strip on said edge and the bottom part of said door being curved downwardly with the threshold whereby upper pressure of the threshold against said 100 part causes the edge of the weather stripping engaging the bottom of the door to slide outwardly to contact therewith.

4. The combination of a door bottom and 105 threshold therebeneath, a weather stripping having a vertically extending part secured to a vertical face of the door near the bottom 110 surface thereof, and a part extending down and curved up into engagement with the bottom face of said door and arranged with its edge normally in contact therewith, said edge being freely slideable with the bottom face of the door, the weather strip on said edge and the bottom part of said door being curved 115 downwardly with the threshold whereby upper pressure of the threshold against said part causes the edge of the weather stripping engaging the bottom of the door to slide outwardly to contact therewith, said edge being 120 hemmed to reduce frictional contact between the door bottom and said weather strip.

GEORGE F. WOLFF.
